UNITED STATES PATENT OFFICE.

HEINRICH AHRENS, OF HALLE-ON-THE-SAALE, GERMANY

ADJUSTING APPARATUS FOR INSTRUMENTS OF PRECISION.

No. 890,394.

Specification of Letters Patent.

Patented June 9, 1908.

Application filed April 13, 1905, Serial No. 255,435. Renewed April 30, 1908. Serial No. 430,154.

To all whom it may concern:

Be it known that I, HEINRICH AHRENS, a subject of the German Emperor, residing at Halle-on-the-Saale, Germany, have invented 5 new and useful Improvements in Adjusting Apparatus for Instruments of Precision, of which the following is a specification.

This invention relates to adjusting apparatus with exchangeable adjusting cones for 10 instruments of precision and the object of the invention is to provide an apparatus that can be used for measuring countersinks of almost any diameter and for ascertaining whether such countersinks are perfectly 15 round or not.

The invention is illustrated in the accompanying drawings in which:—

Figure 1 is a longitudinal section the pin *e* being shown in plan and Fig. 2 a section on 20 the line 2—2 of Fig. 1. Fig. 3 is a view of one of the cones.

In this drawing, *a* indicates the case screw threaded at *b*, and having an enlarged end, containing the longitudinal recess *a'* and the 25 transverse openings *a''*, which are adapted to receive the cheeks *g*. The recess *a'* is continued up into the smaller part of the case *a* as shown at *a³*. This portion *a³* is smaller in diameter than the recess *a'*. A slot *a^X* extends diametrically through the case *a* and communicates with the upper part of the recess *a³*. The adjusting cones *f* fit in the recess *a'* and their shanks *f'* extends up into the recess *a³*. A jam nut *c* screwed on the screw 30 threads *b* of the case, carries a flanged ring *k*, the flanges of which support a non-rotatable ring *d* into which a supporting pin *e* is screwed. This pin *e* extends through the slot *a^X* and through a hole *h* in the shank *f'* of

the adjusting cones. A scale *i* is provided 40 on the case *a*. By turning the nut *c* the ring *d* is caused to move downwardly carrying the pin *e* with it and thus the cones are forced down and push the cheeks outwardly against the edge of the countersink being measured. 45 If the diameter from edge to outer edge of the cheeks "g" amounts to 70 mm. then this diameter is increased, for example, to 85 mm. simply by means of screwing down jam-nut "c" until the lower edge of the ring stands 50 on the desired mark of the scale. While this movement is carried out the action of the cone arrangement causes cheeks "g" to be pressed outward and to be adjusted to the desired diameter. 55

In order that a larger number of diameters may be measured with the same case, cone "f" is rendered exchangeable. The exchanging is effected by unscrewing pin *e* and removing the cone and inserting the new 60 cone.

Having now described my invention what I claim is:—

An adjusting device of the class described comprising a case, radial cheeks carried thereby, an interchangeable cone for actuating said cheeks, a nut *c* movable on said case, a non-rotatable ring carried by said nut, and a pin carried by said ring, said pin being connected to the cone, substantially as 65 described.

In testimony whereof I have signed my name to this specification in the presence of two subscribing witnesses.

HEINRICH AHRENS.
